UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

UNDERFRAME.

1,021,215.

Specification of Letters Patent. Patented Mar. 26, 1912.

Application filed August 10, 1910. Serial No. 576,577.

To all whom it may concern:

Be it known that I, JOHN M. ROHLFING, residing at St. Louis, Missouri, and being a citizen of the United States, have invented 5 certain new and useful Improvements in Underframes, of which the following is a full, clear, and exact description, such as will enable others skilled in the art to which it appertains to make and to use the same, 10 reference being had to the accompanying drawings, which illustrate the preferred form of the invention, though it is to be understood that the invention is not limited to the exact details of construction shown and 15 described, as it is obvious that various modifications thereof will occur to persons skilled in the art.

In said drawings: Figure 1 is a plan view of the end portion of an underframe embodying the features of the present invention. Fig. 2 is an end view thereof. Fig. 3 is a longitudinal, vertical, central section. Figs. 4 and 5 are transverse vertical sections taken respectively on the planes indicated 25 by lines 4—4 and 5—5 of Fig. 1. Fig. 6 is a detail vertical section taken on the plane indicated by line 6—6 of Fig. 1.

In carrying out the preferred embodiment of the present invention, an end section of 30 underframe is provided which comprises a bolster and end sill and diagonal braces, all cast integral and designed to receive side and center sills of commercial, rolled shapes for producing a unitary underframe structure.

The structure is especially adapted for use where it is desirable to have the buffing shocks distributed in part to the side sills between the bolster and end sill. This distribution 40 obviously relieves the diagonal braces of some of the strain to which they would otherwise be subjected, and thus the diagonal braces may be reduced to a minimum section, and a more effectual and uniform balance in the distribution of metal 45 may be provided in all parts of the casting, and the end section rendered rigid throughout, without the employment of parts of excessive weights.

Referring to the details, A is the bolster 50 which is cast integral with the diagonal braces B—B, the outer ends of which braces are cast integral with the end sills C in the rear of the buffing portion thereof. Rolled 55 Z section center sills D—D and similar side

sills E—E, connect the bolster and end sill as hereinafter mentioned.

End sill C comprises a vertical web 1 having upper flange 3 and lower flange 4. Web 1 is formed centrally with the usual draw 60 bar opening, and tapers therefrom to its ends. Flange 3 projects outwardly from and extends longitudinally of the upper edge of the web, and tapers from buffing portion 2 of the end sill to the ends thereof. 65 Flange 4 extends horizontally inwardly in the planes of the lower portions of braces B, said flange 4 terminating at the point of union of the diagonal braces B with the end sill, the flange 4 thus being divided into two 70 sections, the inner end of each section being formed integral with, and continuous of the respective lower flange of the given diagonal brace B. A push pole pocket 6 is formed integral with each end of and extends outwardly from the sills C, and, in the rear of each of said pockets the flange 4 is widened and formed integral with a bracket 5, providing a seat for the end of the respective side sills E, said side sill abutting against 80 the end sill and having its flanges riveted to the bracket 5 and flange 4.

Each brace B comprises a vertical web 7, an upper flange 9, and lower flange 8, the upper flanges of said braces having their 85 outer ends formed integral with a connecting web 9' immediately in the rear of the buffer 2, which web 9' connects the braces B—B and likewise connects said braces with the end sills.

The bolster A is substantially U-shape in general cross section comprising a bottom web portion 9^a, vertical flanges or walls 10 and lateral flanges 11. The forward or outer flange 11 is formed integral with and continuous of the inner ends of the upper flanges of the diagonal braces B—B. The vertical walls 10 of the bolster are connected by cross webs 12—12 and are formed centrally with flanged openings 13 for the passage therethrough of the center sills D, D, said sills being riveted to the outer flanges 13^a and likewise to the inner flanges 13^b or cross connecting walls which latter are best shown in Figs. 1 and 3 whereby said center sills serve as connectors for the bolster walls near the middle of said bolster. It will be noted that the connecting flanges or walls 13^b are of less height than the general bolster structure, thus permitting the top flange 110

of the Z-shaped center sills, to overlap said walls while the outer flanges 13^a terminate above the opening 13, thus permitting the lower flanges of said sills to underlie said flanges 13^a, as best shown in Fig. 4. It will be noted that the center sills D, D, are continuous through the bolsters to the end sills.

A bolster filler casting 14 is formed integral with the walls of the bolster between the center sills, and extends downwardly to form a center bearing 15. The ends of the bolster are formed with seats for snugly receiving the side sills, each of such seats comprising an outstanding portion 16 of the web of the bolster underlying the lower flange of the respective side sills, an integral, vertical cross web 17 connecting the side walls of the bolster, and a horizontal cross web 18 also connecting said side walls and being formed integral with the upper edge of the vertical web 17 and projecting laterally of the bolster as shown in Fig. 1. Said web 18 is depressed below the upper edge of the main portion of the bolster for receiving the upper flange of the respective side sill.

The flanges of the side sills are riveted to the sill seats of the bolster, and the side sills extend beyond the bolster, and abut against the end sill and engage brackets 5 and are rigidly connected thereto. The center sills D also extend beyond the bolster to and abut against the end sill in the rear of the buffing portion and are riveted to the inwardly extending brackets 19, 19, formed integral with and extending inwardly from the end sills.

The rigid connection of the side and center sills to the bolster and to the end sill forms a unitary rectangular structure of exceptional rigidity relative to weight and cross section of the parts, the arrangement also adapting the side sills to receive portions of the buffing stress independently of the diagonal braces which braces in consequence are reduced to a minimum cross section.

The inner vertical wall of bolster A is provided intermediate its length, between center and side sill, with inwardly extending flanges forming pockets 20, 20, for receiving the ends of longitudinal nailing strips 21 and the outer vertical wall of said bolster is formed with similar pockets 22, 22, 55 for receiving the inner ends of short stringers 23, 23, which stringers are interrupted intermediate their length by the diagonal braces B, the ends of such interrupted portions resting in pockets 24 and 25 formed 60 in said brace. The outer ends of the outer sections of stringers 23 engage pockets 26 opening inwardly from the inner face of sill C.

What I claim is:—

65 1. In a car underframe, a unitary struc-

ture comprising a bolster, braces cast integral therewith and provided with stringer pockets, an end sill cast integral with the braces, and a separately formed center sill connecting the bolster to the end sill.

2. In a car underframe, a unitary structure comprising a bolster, braces cast integral therewith and provided with stringer pockets, an end sill cast integral with the braces, and separately formed center sills extending through the bolster and connecting the same to the end sill.

3. In a car underframe, a unitary structure comprising a bolster, braces cast integral therewith and provided with stringer pockets, an end sill cast integral with the braces, and separately formed center sills extending beyond the bolster and abutting against the end sill and connecting the bolster to the end sill.

4. In a car underframe, a unitary structure comprising a cast bolster, braces cast integral therewith and provided with stringer pockets, a cast end sill cast integral with the braces, and rolled center sills extending through the bolster and connected to the bolster and end sill.

5. In a car underframe, a unitary structure comprising a cast bolster, braces cast integral therewith, a cast end sill cast integral with said braces and provided with stringer pockets, and separately formed side and center sills extending beyond the bolster and abutting against the end sill.

6. In an underframe, the combination of a bolster, end sill and diagonal braces and provided with stringer pockets connecting the end sill and bolster and cast integral therewith, and separately formed means connecting the bolster and end sill for forming a rigid rectangular frame of the connected parts.

7. A bolster substantially U-shape in cross section, the vertical walls of the bolster being provided with stringer pockets and terminating short of the ends of the web, and vertical webs connecting the vertical walls at the ends thereof and extending upwardly from the outstanding portions of the first mentioned web and terminating in horizontal cross webs connecting said vertical walls, said webs being dimensioned to fit side sills of Z section.

8. In an underframe, the combination of a bolster comprising a body portion substantially U-shaped in cross section, the vertical walls of the bolster terminating short of the ends of the web, a vertical web connecting the vertical walls at each end thereof and extending upwardly from the outstanding portion of the first mentioned web and terminating in a horizontal cross web connecting said vertical walls, said webs being dimensioned to fit side sills of Z section.

9. In an underframe, the combination of a bolster comprising a body portion substantially U-shape in cross section, the vertical walls of the bolster terminating short of 5 the ends of the web thereof, and vertical webs connecting the vertical walls at the ends thereof and extending upwardly from the outstanding portions of the first mentioned web and terminating in horizontal 10 cross webs connecting said vertical walls, said webs being dimensioned to fit side sills of Z section, an end sill, diagonal braces formed integral with the end sill and with said bolster, and side sills of Z section having 15 their lower flanges fixed to the first mentioned web of the bolster and their upper flanges fixed to the said horizontal cross webs, the said side sills extending and being fixed to the end sill.
- 20 10. An end sill comprising a vertical web, an integral horizontal flange extending inwardly therefrom, stringer pockets above said flange a bracket extending inwardly from the inner face of each end of the vertical web and each comprising a horizontal and a vertical web both formed integral with the first mentioned vertical web and the vertical web of each bracket being also formed integral with said flange, a portion 25 of the flange at each end and the respective bracket being dimensioned to snugly receive a side sill of Z section.
11. In an underframe, the combination of an end sill having inwardly extending 30 flanges forming stringer pockets and a longitudinally extending horizontal flange, and a bracket at each end of the end sill formed integral with the end sill and its flange, each of the brackets with the respective end portion of the flange being dimensioned to 35 snugly receive a side sill of Z section, a bolster, braces formed integral with the bolster and the end sill, and side sills of Z section fixed to the bolster and fixed to 40 said brackets and end portions of the flanges of the end sill.
12. In an underframe, the combination of an end sill having a buffering block, a bolster, diagonal braces formed integral with the 45 ends of the bolster and with the end sill in the rear of the buffering block, and separately formed sills connecting the ends of the bolster to the ends of the end sill, said end sill and said bolster each being formed with 50 stringer pockets.
13. In an underframe, the combination 55
- with a bolster, an end sill, and diagonal braces formed integral with the bolster and with the end sill and having flanges connected by an integral web, each of said members being formed with stringer pockets. 60
14. In an underframe, the combination of a bolster having a flange dipped downwardly to form stringer pockets, an end sill, and diagonal braces formed integral with the end sill and bolster and having flanges formed integral with the flange of the bolster. 65
15. In an underframe, the combination of a bolster, an end sill having a flange, diagonal braces formed integral with the bolster and with the end sill and having flanges formed integral with the flange of the end sill, said flanges serving as stringer pockets. 70
16. In an underframe, the combination of a bolster having a flange forming a stringer pocket, an end sill having a flange, and diagonal braces formed integral with the bolster and with the end sill and having flanges formed integral with the flanges of the bolster and end sill. 75
17. In an underframe, a bolster, an end sill and diagonal braces connecting the end sill and bolster, each of said braces comprising a Z-section having oppositely opening stringer pockets formed integral therewith intermediate the ends of the section. 80
18. In an underframe, a cast bolster comprising side walls perforated for the passage therethrough of continuous center sills and a connecting member therefor, one of said walls being formed with inwardly opening stringer pockets, and the other wall being formed with outwardly opening stringer pockets. 85
19. In a car a car underframe, the combination comprising an integral end sill, diagonal braces and a bolster, said bolster being provided with through openings for the passage of center sills and with vertical walls or flanges at opposite sides of each opening for attachment to a center sill and center sills extending through said openings, said center sills being connected with said bolster walls and with said end sill. 90
- In witness whereof I have hereunto set my hand in the presence of two witnesses. 95
